UNITED STATES PATENT OFFICE.

DANIEL A. KEATING, OF BRIDGEPORT, AND JAMES B. TATEM, OF PUTNAM, CONNECTICUT, ASSIGNORS OF ONE-HALF TO THE AMERICAN TUBE & STAMPING COMPANY, OF BRIDGEPORT, CONNECTICUT, A CORPORATION OF CONNECTICUT, AND ONE-HALF TO JAMES B. TATEM, DOING BUSINESS AS JAMES B. TATEM & SON, OF PUTNAM, CONNECTICUT.

PICKER STICK.

Application filed June 19, 1924. Serial No. 720,953.

To all whom it may concern:

Be it known that we, DANIEL A. KEATING and JAMES B. TATEM, citizens of the United States, residing at Bridgeport and Putnam, respectively, in the counties of Fairfield and Windham, respectively, and State of Connecticut, have invented certain new and useful Improvements in Picker Sticks, of which the following is a specification.

This invention relates to an improved construction of combination wood and metal picker stick of the type employed to drive the shuttle across a loom; and the object of this invention is to provide a picker stick of this character having its upper portion of wood and its lower portion of metal in tubular form thereby obtaining the required resiliency of the wood and at the same time obtaining the increased strength of the metal for absorbing the hammer-like shocks of the shuttle in receiving and throwing the shuttle across the loom.

A further object of this invention is to form the upper end of the tubular metal portion to provide a socket for the reception of the lower end of the wooden portion, also where the stick is pivotally mounted to pierce the side walls near the lower portion of the tubing forming inwardly-projecting flanges about the hole to receive the pivot pin on which the device may swing.

With these and other objects in view, the invention consists of certain novel features of construction, as will be more fully described, and particularly pointed out in the appended claims.

In the accompanying drawings:

Figure 1 is a side elevation of our improved combination wood and metal picker stick, showing the lower end of the wooden portion as inserted into the tubular upper end of the metal portion.

Figure 2 is an edge view of the picker stick.

Figure 3 is an enlarged section on line 3-3 of Figure 1, showing the metal tubular portion as folded into rectangular shape.

Figure 4 is a section on line 4-4 of Figure 1, showing the inturned stock of the side walls about the pivot pin to form extended bearings therefor.

It is found in the practical construction

and operation of picker sticks for looms that, when made entirely of wood their operating life, owing to the severe hammering treatment to which they are subjected, is very short. It is also found that in securing the strength of an all-metal picker stick it must also be extremely light and at the same time should have the resiliency or substantial yieldability of the all-wooden picker stick which is usually formed of hickory. Therefore, in order to combine these requirements of strength and yieldability, we have formed a picker stick of combined metal and wood, the wood providing the elasticity while the metal provides the necessary strength about those portions where this greater strength is required.

By this construction, when one portion of the stick is broken and thrown away the unbroken portion can be remounted in the fresh portion; and the following is a detailed description of one embodiment of our present invention by which these advantageous results may be accomplished:

With reference to the drawings, 10 designates the upper portion of our improved construction of picker stick which is formed of wood, usually hickory, the same being 80 preferably rectangular in cross section larger at its lower end and tapering towards its outer end. This wooden portion is preferably formed of a length substantially one half that of the entire stick but its length 85 may be of any desired proportion thereof.

The lower portion of this stick is herein shown as being made in tubular form as at 11 and the tube may be made in any desired manner and of any desired shape in cross 90 section, but we preferably form the same of sheet metal and fold this metal to form side walls 12 and edge walls 13 and 14, rectangular in cross section. The edges of the strip of metal are caused to abut at 15 along the length of the tube to form the edge wall 14 thereof.

The upper end of this tube is shaped to provide a socket for the correspondingly shaped end of the wooden portion and this 100 wooden portion may be secured to the metal portion by any suitable means.

Near the lower end of this tubular member, I have pierced the side wall 12 as at

18 and turned the stock inwardly about the piercing as at 17 forming elongated bearing portions for the reception of the pivot pin (not shown) on which the picker stick 5 oscillates when of the type to be mounted on a pin for this purpose.

In some instances, we also form the side walls 12 a little longer than the edge walls 13 and 14 thereby providing a groove or recess 19 in the end of the metal portion for the reception of the return strap (not shown).

Near the upper end of the metal portion, we have also provided a series of holes 20 to which the operating mechanism may be connected.

We do not wish to be limited to mounting our improved picker stick to oscillate upon a pivot pin as other suitable means 20 for supporting the lower end may be employed.

Our improved picker stick is extremely simple and practical in construction and effective in its operation and its working 25 life is much longer than that of the all-wood picker stick and at the same time will give the required resiliency which has heretofore been obtained by an all-wooden picker stick.

30 The foregoing description is directed solely towards the construction illustrated, but we desire it to be understood that we reserve the privilege of resorting to all the mechanical changes to which the device is 35 susceptible, the invention being defined and limited only by the terms of the appended claims.

We claim:

1. A picker stick having its upper portion 40 of wood and its lower portion formed of a single piece of metal in tubular form throughout its length.

2. A picker stick having its upper portion of wood and its lower portion of a 45 single piece of sheet metal folded into tubular form.

3. A picker stick having its upper portion of wood and its lower portion of a single piece of sheet metal folded into tubular form angular in cross section throughout its length.

50 4. A picker stick having substantially its upper half of wood and its lower half of a single piece of sheet metal folded into tubular form angular in cross section throughout its length, its opposite side walls being pierced to receive a pivot pin.

55 5. A picker stick having its upper portion of wood and its lower portion formed 60 of a single piece of metal of tubular form throughout its length formed to provide a socket at its upper end for the wood, and spaced apart side walls at its lower end pierced to provide bearings for the pivot pin.

6. A picker stick having its upper portion of wood and its lower portion of a single piece of metal in tubular form, the upper end of the tube being formed to receive and closely embrace the lower end 70 of the wood, and its lower end having its opposite walls pierced to receive and provide a bearing for a pivot pin.

7. A picker stick having its upper portion of wood and its lower portion of sheet 75 metal folded into tubular form, the upper end of the tube being formed to receive and closely embrace the lower portion of the wood and the walls of its lower portion being pierced to receive a pivot pin.

8. A picker stick having its upper portion of wood and its lower portion of sheet metal folded into a tube rectangular in cross section and formed at its upper end to receive the end of the wood and the side 85 walls of its lower portion being pierced to receive the pivot pin.

9. A picker stick having substantially its upper half of wood and substantially its lower half of sheet metal folded into tubular form, the upper end of the tube being formed to receive the wood and the walls adjacent its lower end being pierced and the stock turned inward about the piercing to provide an elongated bearing for the 95 pivot pin.

10. A picker stick having its upper portion of wood and its lower portion of sheet metal folded into a tube rectangular in cross section and formed at its upper end to receive the end of the wood and the side 100 walls of its lower portion being pierced to receive the pivot pin, said side walls being formed to extend beyond the end walls to form a guide for a return strap.

11. A picker stick having substantially its upper half of wood, and substantially its lower half of sheet metal, said metal portion being folded into tubular form to closely fit said wooden upper half.

115 12. A picker stick having substantially its upper half of wood, and substantially its lower half of sheet metal, said metal portion being folded into tubular form to closely fit said wooden upper half, and portions extending inwardly near the lower end of said stick to provide extended bearings for the picker stick pivot pin.

13. A picker stick having substantially its upper half of wood and its lower half of a single piece of sheet metal having its body portion folded into angular form and shaped at its upper end to closely embrace the lower end of the wooden portion and its lower end being folded to form opposite side walls in both of which the pivot pin receives its 120 bearings.

14. A picker stick comprising an upper wooden member having an angular lower portion, a lower sheet metal member folded 125

to form a tube having opposite side walls and opposite edge walls adapted to closely embrace said upper member, and means for connecting said members together.

5 15. A picker stick comprising an upper wooden member and a lower sheet metal member, said lower member having portions

extending inwardly near its lower end to provide a bearing for the pivot pin on which the picker stick is mounted. 10

In testimony whereof we affix our signatures.

DANIEL A. KEATING.
JAMES B. TATEM.
